HEARTH PLATE.

No. 15,417.

Patented Sept. 16, 1884.

UNITED STATES PATENT OFFICE.

JOSEPH A. READ, OF PHILADELPHIA, PENNSYLVANIA.

DESIGN FOR A HEARTH-PLATE.

SPECIFICATION forming part of Design No. 15,417, dated September 16, 1884.

Application filed July 21, 1884. Term of patent 7 years.

To all whom it may concern.

Be it known that I, JOSEPH A. READ, a citizen of the United States, and a resident of Philadelphia, Pennsylvania, have invented or produced a new and original Design for a Hearth-Plate, of which the following is a specification.

My design for a hearth-plate is fully shown by the accompanying photographic illustration. The plate has radiating grooves, and an ornamental border comprising upper and lower beaded bands, and an intermediate portion of ogee shape, with a line of ornamentation in relief running around it.

I claim—

The design for a hearth-plate, said design consisting of the ornamentation substantially as shown and described.

In testimony whereof I have signed my name to this specification in the presence of two subscribing witnesses.

JOSEPH A. READ.
